United States Patent Office

Des. 230,571
Patented Mar. 5, 1974

230,571

CONTAINER FOR EDIBLE POWDERS OR THE LIKE

Richard C. Allen, 22 W. 341 Balsam,
Glen Ellyn, Ill. 60137

Filed July 11, 1972, Ser. No. 270,718

Term of patent 14 years

Int. Cl. D9—03

U.S. Cl. D9—216

FIG. 1

FIG. 2

FIG. 3

FIG. 1 is a top plan view of a container for edible powders or the like showing my new design;

FIG. 2 is a side view thereof; and

FIG. 3 is a bottom view thereof.

I claim:

The ornamental design for a container for edible powders or the like, as shown.
